[57] CLAIM

The ornamental design for a wheeled trolley for multiple bins, as shown and described.

DESCRIPTION

FIG. 1 is a perspective view of a wheeled trolley for multiple bins embodying my/our new design;

FIG. 2 is a right side view of a wheeled trolley for multiple bins of FIG. 1, the left side being a mirror image thereof;

FIG. 3 is a top view of a wheeled trolley for multiple bins of FIG. 1;

FIG. 4 is a front view of a wheeled trolley for multiple bins of FIG. 1;

FIG. 5 is a rear view of a wheeled trolley for multiple bins of FIG. 1;

FIG. 6 is a top view without lid of a wheeled trolley for multiple bins of FIG. 1; and,

FIG. 7 is a bottom view of a wheeled trolley for multiple bins of FIG. 1.
